UNITED STATES PATENT OFFICE.

ALFRED STROMBERG, OF CHICAGO, ILLINOIS, ASSIGNOR OF ONE-HALF TO
MARKS SIMONS, OF SAME PLACE.

BURGLAR-ALARM CABINET.

SPECIFICATION forming part of Letters Patent No. 486,908, dated November 29, 1892.

Application filed July 9, 1892. Serial No. 439,489. (No model.)

To all whom it may concern:

Be it known that I, ALFRED STROMBERG, a citizen of the United States, residing at Chicago, in the county of Cook and State of Illinois, have invented a certain new and useful Improvement in Burglar-Alarm Cabinets, (Case No. 4,) of which the following is a full, clear, concise, and exact description, reference being had to the accompanying drawings, forming a part of this specification.

My invention relates to burglar-alarm protection for safes; and its object is to provide a cabinet surrounding a safe, to which cabinet a burglar-alarm circuit is attached, and which may be opened readily to give access to the safe without the inconvenience of shutters or swinging doors.

My invention consists in a case or cabinet which is adapted to fit the safe or safes which it is intended to protect, this cabinet being provided with the burglar-alarm circuit described in my patent, No. 483,728, dated October 4, 1892, and provided with a flexible curtain so placed that it may be raised to give access to the safe-door, and in other features of construction, which I will now proceed to explain.

Referring to the drawings, Figure 1 shows a front elevation of a cabinet adapted to protect three safes. One curtain is shown raised, thus exposing the safe. Fig. 2 shows the detail of one of the stanchions which divides the front of the cabinet. Fig. 3 shows the contact-spring in the groove in which the curtain slides depressed by the curtain. Fig. 4 shows a portion of one of the swinging stanchions which I employ. Fig. 5 is a diagram of the circuits. Fig. 6 shows the method of mounting the tin-foil upon the rigid portion of the cabinet.

Similar letters of reference refer to similar parts throughout the different views.

The cabinet *a* is adapted to entirely surround the safe and is protected by the circuit described in my application, Serial No. 425,030. The curtain or flexible front *b* of the cabinet is adapted to be lifted and carried back through a place provided for it over the top and back of the safe. The method of making this flexible curtain or front of the cabinet is well known, and as it is not an essen-

tial feature of my invention I do not deem it necessary to describe it further. Upon the sill *c* of the opening, upon which the curtain falls when it is closed, I arrange contact-points, by means of which the circuit through the curtain is closed when the curtain is closed. To carry the curtain far enough beyond the front of the vault to avoid contact with the handles of the safe-door, I provide the stanchions *d d* in which the curtains slide with hinges which permit them to be swung, as shown in Fig. 4. In these stanchions is provided the channel *c'*, which acts as a guide to the flexible curtain. These hinged stanchions are also protected with a burglar-alarm circuit, as is the rest of the cabinet, and in these stanchions is also provided the contact-spring *d'*, one spring being placed in each channel of each stanchion. Where only one safe is to be protected in the manner described, I omit the intermediate stanchions *e e*. The detail of the stanchion *e* is shown in Fig. 2. These stanchions are made removable at will, so that when access is desired to the safes protected by the cabinet the curtain may be raised and the stanchions removed, thus giving free access to the safes.

The dogs *ff* at the top of the stanchions are adapted to fit recesses *f' f'* upon the upper part of the cabinet-frame. The spring contact-point *g* is adapted to press a plate in the upper part of the cabinet-frame, thus closing the circuit between the cabinet-frame and the conductor upon the stanchion. The circuits through the various parts of the cabinet are shown in Fig. 5. Upon the inner face and close to the bottom of the stanchions *e e* I arrange contact-plates *e'*, connected with the circuit on said stanchions, as shown in Fig. 3. These contact-plates are adapted to press upon springs on sill *c*, thus making the circuit complete through the stanchions. Upon the inner face of each of the swinging stanchions *d d* I provide contact-plates similar to *e'*, so that when the said stanchions are swung to said contact devices are adapted to close circuit in the same manner as the contact devices situated upon the stanchions *e e*. The spring-contacts *g*, by means of which, in connection with said contact-plates, the circuits are closed, are placed upon the front of the

cabinet, one being placed near the top and the other near the bottom, and mounted upon a permanent stanchion d^2 . (Shown in Fig. 4.) The circuit-closing spring d' is connected into 5 circuit with the contact-point g and is adapted to close the circuit through the curtain when the curtain is drawn completely down. The circuit is then complete through the stanchion, the curtain, and the rigid part of the 10 cabinet which covers the top, bottom, and three sides of the safe, and any disarrangement of the curtain or of the stanchions or any penetration of the cabinet will result in 15 disarrangement of the circuit and the sending of an alarm in the manner described in my application, Serial No. 425,030. For convenience a switch h is provided, as described in the aforesaid application, for switching off the circuit from the cabinet before the 20 curtain is raised when it is desired to get access to the safe by any one who is authorized to do so. A lock may be provided to secure the curtain when drawn down, although this is not usually required. In Fig. 25 6 I have shown the detail of the arrangement of circuits which I use for protecting the rigid portion of the cabinet—that is, the part covering the top, bottom, three sides, and a portion of the front. The wide strip l of tin-foil 30 is placed upon the inner side of the cabinet, either directly upon the wood or upon some covering of the cabinet. Between this and the strip m I place the insulating material (preferably paper) n , the strip n being placed at 35 right angles to the strip l . These two strips of tin-foil are adapted to form the two sides of the circuit, as shown in the diagram of circuits in Fig. 4. This diagram will be readily understood in connection with my application 40 Serial No. 425,030.

I have shown the apparatus at the central office simply in diagrammatic form. The circuit passes from ground through the battery and central-office apparatus, through the top, 45 through one side, the back, the other side, the bottom, and the front of the cabinet, thence to the hinged stanchion d , through the curtains to the resistance-coil o , thence by means of the contacts upon the sill c to the 50 curtains through strips placed thereon at right angles to the circuit already described, thence through the other curtains, back through the sides, front, bottom, and back through the other side and top of the cabinet to ground 55 at p .

I claim—

1. In a cabinet entirely surrounding a safe, the combination, with the flexible curtain adapted to be raised to give access to the safe-door, of the swinging stanchions d , 60 provided with channels c' , which act as guides to said flexible curtain, and a sill c , upon which said curtain is adapted to fall, and contact-points on said sill, adapted to make contact with plates connected to the 65 circuits which are carried by said flexible curtain, substantially as and for the purpose specified.

2. In a cabinet surrounding a safe, the combination, with the flexible curtain adapted to 70 be brought down over the face of the safe, of the swinging stanchion d and the stanchion e , each provided with channels which serve as guides for the said curtain, whereby the said curtain is directed to the sill c , contact-points carried upon said curtain and said stanchions and adapted to complete an electric circuit, whereby when said curtain or said stanchions are removed from their normal 75 positions said circuit may be broken to give 80 an alarm, substantially as and for the purpose specified.

3. The combination, with a cabinet carrying an electric circuit, of a flexible curtain carrying an electric circuit and adapted to close an 85 opening in said cabinet, stanchions carrying slots in which said curtain is adapted to slide, and contact-points carried upon said curtain and said stanchions and adapted to complete an electric circuit, whereby when said 90 curtain or said stanchions are removed from their normal positions, said circuit may be broken to give an alarm, substantially as described.

4. The combination, with a cabinet carrying 95 an electric circuit, of a flexible curtain carrying an electric circuit and adapted to close an opening in said cabinet, a swinging stanchion and a removable stanchion, said stanchions carrying slots in which said curtain is adapted to slide, and contact-points carried upon said cabinet, curtain, and stanchions, whereby when said curtain or said stanchions are displaced from their normal 100 positions the circuit may be broken to give 105 an alarm, substantially as described.

In witness whereof I hereunto subscribe my name this 7th day of July, A. D. 1892.

ALFRED STROMBERG.
